UNITED STATES PATENT OFFICE.

WILLIAM HARRY WATSON, OF ST. PETERS, NEAR SYDNEY, NEW SOUTH WALES,
AUSTRALIA.

EAVE-GUTTER BRACKET AND OVERSTRAP.

1,235,619.

Specification of Letters Patent.

Patented Aug. 7, 1917.

Application filed April 18, 1917. Serial No. 163,015.

To all whom it may concern:

Be it known that I, WILLIAM HARRY WATSON, a subject of the King of Great Britain and Ireland, residing at 83 Lymerston street, 5 St. Peters, near Sydney, New South Wales, aforesaid, Australia, have invented certain new and useful Improvements in Eaves-Gutter Brackets and Overstraps, of which the following is a specification.

10 According to present practice eave gutters are mounted on spike brackets, on cast brackets, or on framed brackets, with overstraps of heavy gage sheet metal.

The object of the present invention is to 15 provide an improved bracket and overstrap of lighter gage sheet metal than that hitherto used, without spike, casting, or frame supports, and adapted if required to be nailed or screwed directly to the building 20 fascia and rafter ends and to be embraced on the gutter bead to secure the gutter against accidental displacement. Manufacture and erection of eave gutters and overstraps is thus facilitated and cheapened, 25 while at least the same security is assured as with brackets and overstraps of types now in use.

The eave gutter brackets in which the present invention consists are constructed by 30 corrugating or embossing the middle portion of a flat strip of metal of suitable light gage but preferably light gage galvanized sheet iron or steel, by cold or hot pressing or embossing and simultaneously bending the strip 35 in the forming operation to the section of the gutter for which it is to be used; both ends, or the lip end only of the strip is left flat and splayed outward. Similarly the overstrap is produced by cold or hot pressing or 40 embossing a strip of suitable light gage sheet metal from end to end and simultaneously bending it at either end to set at one end over the rafter ends and at the other to set against the inturned flat lip end of 45 the bracket.

The lip end of the bracket is rolled around the gutter bead to embrace it and secure the gutter in the bracket, and the over rolled edge may be soldered to the gutter metal to 50 afford better security against accidental displacement. The flat butt end if same is left on the bracket in manufacture may be laid over the top edge of the fascia boards or over the rafter ends, or may be cut off; the

bracket is mounted on the front of the fascia 55 board or on the rafter ends by nails or screws driven through holes made in the erect portion of the bracket which sets against said fascia or rafters. The overstrap is nailed to the upper outer end of the 60 rafter and its free end is secured to the gutter and the rolled end of the bracket by a through bolt.

In the accompanying drawings Figure 1 is a longitudinal section through an eave 65 gutter bracket according to this invention, showing the bracket blank with butt and lift flats as produced by cold or hot pressing or embossing a strip of relatively thin sheet metal; Fig. 2 is a perspective view showing 70 one of the brackets fixed to a fascia board, ready for the setting of the gutter; and Fig. 3 is a transverse section showing one of the brackets fixed as in Fig. 2, and having the flat lip end portion closed over the gutter 75 bead, and the overstrap fixed and secured thereto by a through bolt.

The corrugations or embossed portions in the bracket and in the overstrap may be of any desired pattern, and are preferably 80 plain wave corrugations of sufficient depth to insure satisfactory stiffness and strength to carry the load and resist deformation by accidental pressures. The form of the bracket (see Fig. 3) corresponds in each 85 case with the transverse section of the eave gutter. A width of one to four inches with corrugations about $\frac{1}{4}$ " deep suffices to offer ample strength in metal 24 to 28 B. W. G. in thickness. Such relatively thin metal 90 permits the driving of screws and nails B to mount the bracket and overstrap without necessitating preliminary drilling or punching of holes therein. A are the corrugations in the bracket; C is the gutter; E the roll 95 edge of the gutter; F the binding lip of the bracket which is bent over the gutter roll E and when desired secured to the gutter metal by soldering. B are the mounting nails or screws, and H the fascia board on which the 100 bracket is mounted. G is the overstrap, and K the through bolt fastening below the gutter bead E.

What I claim as my invention and desire to secure by Letters Patent is:—

1. An eave gutter support comprising a bracket of light gage sheet metal bent to correspond with the gutter section and cor-

ruggated transversely of such section, with a flat overfolding lip and adapted to be folded over the gutter bead, and an over-strap of similar metal corrugated from end to end and adapted to be secured to a rafter and bolted to the gutter and bracket fold substantially as herein described.

2. An eave gutter bracket consisting of a strip of light gage sheet metal bent to include a gutter section and simultaneously corrugated in the bent portion in a direction transverse to the gutter length, leaving a flat extension at one end of the corrugations.

3. An eave gutter bracket consisting of a bent corrugated strip of light gage sheet metal with a flat end portion adapted to be

wrapped over the roll edge of an eave gutter, substantially as described.

4. An eave gutter overstrap consisting of a strip of light gage sheet metal bent to conform to the rafter pitch at one end, at the other end bent substantially at right angles to its length to set against the gutter lip, and corrugated from end to end by pressing or embossing. 20 25

In testimony whereof I affix my signature in the presence of two witnesses.

WILLIAM HARRY WATSON.

Witnesses:

W. J. HUMPHREYS,
W. I. DAVIS.
